UNITED STATES PATENT OFFICE.

ERNEST H. SHAFF, OF GRAND HAVEN, MICHIGAN, ASSIGNOR TO WILLIAM H. KELLER, INC., OF GRAND HAVEN, MICHIGAN, A CORPORATION OF MICHIGAN.

FLUID-PRESSURE-ACTUATED TOOL.

Application filed October 16, 1920. Serial No. 417,320.

My invention relates to fluid-pressure-actuated tools and more specifically to an improvement in tools of the general type disclosed and claimed in my copending application Serial No. 371,445, filed April 5, 1920.

One object of the invention is to provide means whereby tools of this type may be operated at slower speeds than heretofore.

Another object of the invention is to provide for a more rapid decrease in the pressure returning the piston toward the end of the stroke than has heretofore been obtainable, thereby reducing the recoil at the end of the return stroke.

15 Further objects and advantages of my invention will become apparent as the description proceeds.

In the accompanying drawings Figure 1 is a sectional view of a pneumatic hammer illustrating the application of my invention thereto and Fig. 2 is a similar view on a somewhat enlarged scale showing the valve in the other position. Fig. 3 is a fragmentary radial section of the tool through the 25 passage 52 shown in Fig. 2. The general construction and operation of this type of hammer being disclosed in detail in my copending application hereinabove referred to, detailed explanation thereof is deemed unnecessary. The tool comprises, briefly, a 30 body member 10 defining a cylinder in which the piston 12 reciprocates to strike a suitable working tool 14; a valve casing comprising annular members 16 and 18 supporting and guiding the valve 20, and a 35 head 22 threaded onto the body and locked in assembled position by a locking clip 24. A throttle valve operated by the lever 26 controls air through passage 28 to an annular chamber 30.

40 With the valve in the position shown in Figure 1 live motive fluid enters through radial passages 32 terminating in the annular groove 34 and forces the piston forward to strike a blow against the tool. The dead air in front of the piston flows from the front end of the tool through one or more 45 passages 36 to the annular groove 38 in the valve casing which, as shown in Fig. 1, is in communication with the exhaust groove 40 from which exhaust groove, passages 42 opening under the clip 24 allow the fluid to escape into the atmosphere.

50 In its forward movement the piston uncovers the small port 44 which raises the

pressure in the passage 46 considerably before the piston toward the end of its stroke covers the end of passage 48 and uncovers the end of passage 46. When this occurs, live motive fluids flows through passage 46 and enters the large valve chamber 50 thereby throwing the valve back immediately to the position shown in Fig. 2. The air in chamber 50 back of the valve flange may escape through passage 51 into exhaust passage 42. During this movement of the valve live motive fluid fills the passage 48 which, after passage 46 has been cut off from the large valve chamber 50, continues to exert pressure on the valve and hold it in its rearmost position.

The movement of the valve to the position shown in Fig. 2 covers groove 34 and uncovers the exhaust groove 40 so that live motive fluid is cut off from the rear portion 55 of the cylinder and the latter is placed in direct communication with the atmosphere. The valve in its rearward movement also uncovers the forward end of a passage 52 putting it into communication with groove 58 and passage 36. Passage 52 extends radially outward at 54 to receive live motive fluid from the annular chamber 30, which fluid is delivered through passage 36 to the front end of the cylinder to return the piston. On account of the relatively small size of passage 52 the pressure during the return stroke will fall off rather rapidly especially toward the end of the stroke when the piston has attained a fairly high velocity. When the piston uncovers passage 48, the pressure of the fluid in this passage will fall to the same pressure as that in the front end of the cylinder, which pressure as above noted will decrease considerably during the 95 return stroke.

Toward the end of the return stroke the piston covers the end of the passage 56, the other end of which communicates with the small valve chamber 58. A small port 60 continuously communicates with this passage and with the annular chamber 30. The pressure in the passage 56 cannot rise during the return stroke because the end of the passage is in communication with the rear end of the cylinder until the piston covers it. When this occurs, the pressure in the passage 56 immediately rises and the valve is thrown forward again into the position shown in Fig. 1. This takes place against 110

the pressure existing at the instant in the large valve chamber 50 which is the same as the pressure in the front end of the cylinder by reason of passages 48 which are continually in communication with the large valve chamber and the front end of the cylinder. As soon as the valve has shifted, however, the front end of the cylinder is again connected to the exhaust passages through passages 36 so that during the forward stroke the pressure in the large valve chamber will be practically atmospheric and the valve will be held firmly in the position shown in Fig. 1.

It is often desirable for the workman to strike one or two light preliminary blows before delivering full power to the tool and for this purpose the supply of air to the tool is throttled. When the supply of air is throttled down by the workman, a limit is reached below which the tool will not operate and this limit occurs when with the piston in its rearmost position and the valve in the position shown in Fig. 2, the supply pressure in the small valve chamber 58 is not sufficient to shift the valve forward. The point at which this limit is reached depends largely on the pressure in the front end of the cylinder, which through passage 48 controls the pressure in the large valve chamber.

According to my invention I provide a small auxiliary port 62 in passage 46 opening under clip 24 directly into the atmosphere. This passage, especially when the supply pressure is low and the volume delivered correspondingly small, will materially cut down the pressure in the front end of the cylinder when the piston is far enough back on its return stroke to uncover passage 46 thereby reducing the pressure in the large valve chamber and making it possible to operate the tool at slower speeds than would otherwise be obtainable.

During the operation of the tool under full pressure it also materially diminishes the recoil at the end of the return stroke by cutting down the pressure returning the piston after the piston uncovers the end of passage 46. It is thus possible by slightly increasing the size of passage 52 to secure the same speed of operation by accelerating the piston slightly faster during the first half of the return stroke and slightly less after passage 46 is uncovered, getting the piston back to the rear end of the cylinder in the same length of time, but with a materially lower final velocity and with less pressure in front of it at the instant of reversal.

While I have illustrated and described in detail the preferred embodiment of my in-

vention, it should be clearly understood that the disclosure is merely for purposes of illustration and that many modifications and variations will naturally occur to those skilled in the art. I aim in the subjoined claims to cover all such legitimate variations and modifications.

I claim as my invention:

1. A pressure-fluid-actuated tool comprising, in combination with a cylinder having a piston, a valve mechanism for controlling the piston comprising a valve member, a small pressure chamber and a large pressure chamber, means for admitting a constant supply of live motive fluid to the small pressure chamber, means including a passage controlled by the piston near the beginning of its forward movement for substantially relieving the pressure in the smaller chamber, means controlled by the piston as it approaches the end of its forward movement for admitting pressure fluid from the piston chamber to the larger pressure chamber whereby to shift the valve member, and means including a passage intermittently opened to exhaust for relieving the pressure in the larger pressure chamber in the return movement of the piston, and substantially before it reaches the end of its stroke, the piston near the end of its return stroke serving to close said passage whereby to effect the forward shifting of the valve member.

2. A pressure-fluid-actuated tool comprising, in combination with a cylinder having a piston, a valve mechanism for controlling the piston comprising a valve member, a small pressure chamber and a large pressure chamber, means for admitting a constant supply of live motive fluid to the small pressure chamber, means including a passage controlled by the piston near the beginning of its forward movement for substantially relieving the pressure in the smaller chamber, means controlled by the piston as it approaches the end of its forward movement for admitting pressure fluid from the piston chamber to the large pressure chamber whereby to shift the valve member, and means including a constantly open exhaust port from said shifting means for relieving the pressure from the cylinder in front of the piston during the latter portion of its return stroke, the piston also serving near the end of its return stroke to close said passage whereby to effect the forward shifting of the valve member.

In testimony whereof, I have hereunto set my hand.

ERNEST H. SHAFF.
